WIRE OPENER ATTACHED BY BOSS TO SCORED CAN END

Henry E. Frankenberg, Berwyn, Ill., assignor to Continental Can Company, Inc., New York, N.Y., a corporation of New York

Filed Sept. 27, 1963, Ser. No. 312,216
1 Claim. (Cl. 220—48)

This invention relates in general to new and useful improvements in container ends, and more particularly to a novel container end having an easy self-opening device.

There are many instances where it is desirable to be able to open a conventional type of container having a metal end without requiring the use of a can opener or other type of special implement. Accordingly, it is the primary object of this invention to provide a novel container end which is equipped with an opening device having a cutter which is engageable with an end panel of the container end and when the opening device is moved, it will effect the rupture and cutting out of a predetermined portion of the end panel.

Another object of this invention is to provide a novel container end unit which includes a container end having an end panel which is provided with a pivot and there being mounted on the pivot an opening device which includes a cutter remote from the pivot, the cutter opposing the end panel and being operable upon being brought into pressure engagement with the end panel and the opening device swung around the pivot to effect a continuous rupture of the end panel and the ultimate removal of a portion of the end panel whereby the contents of the container may then be dispensed.

Still another object of this invention is to provide a novel container end unit which includes a container end having an end panel, an opening device pivotally carried by the end panel and having a cutter engageable with the end panel to effect the rupture of the end panel and the removal of a portion thereof to define a dispensing opening, the end panel being provided with a pocket normally loosely receiving the cutter of the opening device whereby accidental rupture of the end panel by handling of the container is prevented.

A further object of this invention is to provide an end panel of a container end with a simple opening device in the form of a rigid wire member which is provided at one end with a loop or ring portion surrounding an integral boss of the end panel, and at the opposite end with a downwardly facing pointed end portion which is engageable with the end panel under pressure to effect the rupture of the end panel and the removal of a portion of the end panel when the wire member is swung about the pivot.

Another object of this invention is to provide a container end unit of the type set forth above wherein the end panel is provided with a pocket for loosely receiving the pointed end of the wire member, and an intermediate portion of the wire member rests upon the end panel to prevent the downward movement of the pointed end whereby accidental rupture of the end panel is prevented.

A still further object of this invention is to provide an end panel unit of the type set forth above wherein the end panel is additionally provided with a pair of upstanding portions disposed on opposite sides of the wire member intermediate portion to prevent the accidental swinging of the wire member to an end panel rupturing position.

Still another object of this invention is to provide a container end unit of the foregoing type with a weakening line to facilitate the rupture of the end panel and a removal of a portion thereof.

With the above and other objects in view that will hereinafter appear, the nature of the invention will be more clearly understood by reference to the following detailed

2

description, the appended claim and the several views illustrated in the accompanying drawing.

In the drawing:

FIGURE 1 is a fragmentary top perspective view of a container incorporating a container end unit in accordance with this invention.

FIGURE 2 is a plan view of the container end unit of FIGURE 1 and shows further the details of the opening device carried thereby, the opening device being shown in an end panel rupturing position by dotted lines.

FIGURE 3 is an enlarged fragmentary vertical sectional view taken along the line 3—3 of FIGURE 2 and shows the specific details of the opening device and the manner in which it is pivotally mounted and the relationship thereof with respect to a pocket which normally receives the cutter of the opening device.

FIGURE 4 is an enlarged fragmentary vertical sectional view similar to FIGURE 3 and taken along the line 4—4 of FIGURE 2, the view showing the opening device in an upward position.

FIGURE 5 is an enlarged fragmentary vertical sectional view taken generally along the line 5—5 of FIGURE 3 and shows more clearly the manner in which the opening device is retained in an inoperative position.

Referring now to the drawings in detail, it will be seen that there is illustrated in FIGURE 1 a container which is generally referred to by the numeral 10. The container 10 is illustrated as being in the form of a can although this invention is not limited to cans.

The container 10 includes a can body 11 which has the illustrated upper end thereof closed by means of a can end, generally referred to by the numeral 12. The can end 12, as is clearly shown in FIGURE 3, is secured to the can body 11 by means of a conventional double seam 13 and includes an end panel 14. The can end 12 differs from a conventional can end in that the end panel 14 is provided with a central boss 15 which includes an upper end wall 16 and a generally semi-circular cross sectional upstanding wall 17.

An opening device, generally referred to by the numeral 18, is carried by the boss 15 for pivotal movement. The opening device 18 is in the form of a wire member 20 which is shaped at one end to define a loop or ring portion 21 which snugly engages the boss 15 and serves to position the wire member 20 relative to the end panel 14. An intermediate portion 22 of the wire member 20 rests directly upon the end panel 14 in the inoperative position of the opening device 18, as is shown in FIGURE 3. The wire member 20 projects upwardly, as at 23, outwardly of the intermediate portion 22 and then extends generally horizontally, as at 24. The wire member 20 terminates in an outer downwardly directed end portion 25 which has a downwardly directed pointed end 26 which functions as a cutter.

In order to permit the handling and shipment of the container 10 without the accidental rupture of the container end 12, the end panel 14 is provided with a downwardly directed portion at 27 to define a pocket 28 which loosely receives the pointed end 26. This is best shown in FIGURE 3. In order to prevent the accidental swinging or pivoting of the opening device 18 during handling, the end panel 14 is also provided with a pair of upstanding projections 29 which are disposed in generally spaced parallel relation and are positioned radially inwardly of the pocket 28, as is best shown in FIGURE 2. The projections 29 are disposed on opposite sides of the intermediate portion 22 of the wire member 20 and serve to prevent the accidental pivoting of the opening device 18 around the boss 15.

In order to facilitate the opening of the container 10 utilizing the opening device 18, the end panel 14 is provided with an interrupted score line 30 which, for the

most part of its extent, extends along the path of movement of the pointed end 26. However, in the vicinity of the pocket 28, the score line 30 is offset, as at 31, to extend slightly inwardly of the pocket 28, as is best shown in FIGURE 2.

During the use of the opening device 18, the horizontal portion 24 is lifted so that the pointed end 26 is removed from the pocket 28 and the intermediate portion 22 of the wire member 20 can pass over one of the projections 29. The pointed end 26 is then lowered into engagement with the end panel 14 along the weakening line 30 and pressure is exerted, preferably by one's thumb, against the horizontal portion 24 of the wire member 20 to effect both a swinging and rupturing pressure on the opening device 18. The opening device 18 is pivoted entirely about the boss 15 until the pointed end 26 reaches the opposite end of the pocket 28. The portion of the end panel 14 defined by the score line 30 may then be folded upwardly along the portion 31 of the score line to effect the removal of the portion of the end panel 14 defined by the score line 30.

It will be readily apparent that no tool is required to open the container end 12 with the exception of the opening device 18. Further, it will be readily apparent that the opening device 18 is so mounted on the container end 12 whereby accidental rupture of the end panel 14 is prevented. In addition, it will be readily apparent that once the opening device 18 has been moved to an operative position, it may be readily utilized to effect the severing of a desired portion of the end panel 14 and the removal thereof.

Although only a preferred embodiment of the invention has been specifically illustrated and described herein, it is to be understood that minor modifications may be made in the container end unit within the spirit and scope of this invention, as defined in the appended claim.

I claim:

An easy opening container end unit comprising a combination of a rigid wire member having an inner ring portion, an intermediate portion adjacent said ring portion, and a generally inverted U-shaped outer portion connected to said intermediate portion, said outer portion terminating in a downwardly directed lower pointed end for rupturing contact with said end panel and including a horizontal upper portion against which pressure is brought to swinging movement, said opening device being in the form of a container end including an end panel, a pivot on said end panel, and an opening device carried by said pivot for bearing in the use of said opening device, said pointed end being disposed within a projection of said end panel in all positions of said pointed end, said end panel having an inwardly offset recess aligned with the path of said pointed end for receiving said pointed end in the storage position thereof, and said end panel having upstanding projections disposed on opposite sides of a line extending between said pivot and said recess for engaging said intermediate portion and preventing accidental rupturing of said end panel by said pointed end.
